WITNESS:

UNITED STATES PATENT OFFICE.

RICHARD WALTER DAWN, OF DEER LODGE, MONTANA.

GARMENT HOLDER AND PROTECTOR.

Application filed July 21, 1926. Serial No. 124,041.

This invention relates to improvements in garment protectors and has for an object the provision of a foldable protector within which a garment may be placed to protect the same, with a portion of the garment exposed for inspection, and the exposed portion protected and separated from other garments.

Another object of the invention is the provision of a garment protector which may be arranged to enclose a garment without folding the latter, or may be folded into compact form for convenience in carrying.

Another object of the invention is the provision of a protector which will hold the bottom of a garment in a relatively restricted manner for convenience in carrying without folding.

With the above and other objects in view, the invention further includes the following novel features and details of construction, to be hereinafter more fully described, illustrated in the accompanying drawings and pointed out in the appended claims.

In the drawings:—

Figure 1 is a plan view of the blank from which the protector is made.

Figure 2 is a view showing the protector in use with a portion of the garment exposed.

Figure 3 is a view of the protector arranged to be folded in compact form, the position of the garment being shown by dotted lines.

Figure 4 is an elevation showing the top panel open.

Figure 5 is a view with the top panel closed and the protector arranged in compact form.

Referring to the drawings in detail wherein like characters of reference denote corresponding parts, the protector is shown as made from a single blank of material, preferably heavy paper and comprises a body panel 10 whose side edges are relatively inwardly inclined as shown by the dotted fold line 11. Extending from these side edges are foldable side panels 12 which are adapted to be folded over upon the body panel. Extending from opposite ends of the body panel 10 are top and bottom panels 13 and 14 respectively and these panels are sepa-

rated from the body panel by the dotted fold lines 15. A transverse fold line 16 extends across the body panel 10 and side panels 12.

In the use of the invention, a garment such as is indicated at 16' is placed within the body panel preferably upon a hanger 17 and the hook 18 of the hanger is passed through a reinforced slit 19 which extends along the upper fold line 15. The side panels 12 are folded over upon the garment and are secured in folded position by a string and button fastening 21, while the top panel 13 is folded over upon the side panels and secured by a string and button fastening 22. The same string employed in connection with the fastening 21 may be utilized for this purpose as may also one of the buttons. When arranged in the position described and illustrated in Figure 2, the garments may be hung in unfolded position with the lower panel 14 forming an apron or separating panel which will divide and protect the exposed portion of the garments from one another when a number of the protectors are hung close together. In addition, the apron will afford protection for the exposed portion of the garment when the latter is being carried as in delivering garments, by preventing clean garments from rubbing against garments which are soiled, while the restricted lower end of the protector, due to the relatively inclined fold lines 11, will draw the bottom of the garment inward and further serve to prevent contact with a person carrying the garment.

If desired, the protector may be folded into compact form for carrying and when so used, the garment is folded into the upper half of the body panel 10 as illustrated by the dotted lines in Figure 3 of the drawings. The side panels 10 are folded over and secured in the manner shown, while the bottom panel 14 is folded upon these folded side panels. The protector is next folded along the dotted fold line 16 so that the body is folded upon itself, after which the top panel 13 is folded and secured to a button 23 as shown in Figure 5.

By unfastening the cord 22 from the button 23 and supporting the protector by the hook 18, the bottom panel 14 will fall down.

ward and the body of the protector will likewise unfold, with the result that the garment within the protector will also be permitted to unfold, so that the lower portion of the garment will be exposed as in Figure 2.

By reference to the drawings, it will be seen that the outer side edges of the side flaps 12 are substantially V-shaped and are so proportioned that when they are folded 10 they will provide substantially triangular openings 24 and 25 at the top and bottom respectively of the protector. This will permit of an inspection of the contents of the protector without opening the side flaps.

15 It will be apparent from the foregoing description, and the accompanying drawings that the invention provides a combined garment holder and protector which may be used within a cleaning or other establishment for the purpose of affording protection for a garment awaiting delivery. It may be readily opened if desired, to permit the customer to inspect the garment before delivery, after which it may be folded into 20 compact form for carrying purposes. Upon delivery, the customer may unfasten the cord 22 as just described and permit the garment to fall to an unfolded position without removing the garment from the protector.

25 The invention is susceptible of various changes in its form, proportions and minor details of construction and the right is here-

in reserved to make such changes as properly fall within the scope of the appended claims.

Having described the invention what is 35 claimed is:—

1. A garment protector comprising a body panel, side panels extending from opposite side edges of and foldable upon the body panel, means to secure the side panels in 40 folded position, a bottom closure panel and a top closure panel, said bottom and top panels being adapted to be folded upon the folded side panels to provide a closed receptacle of the same area as the body panel, said 45 receptacle being foldable upon itself to reduce its area substantially one-half and means to secure the receptacle in folded form with the top panel folded over and secured to the outer face of the body panel, where- 50 by, when the last mentioned securing means is released both the bottom panel and receptacle will be permitted to unfold.

2. A garment protector comprising a body panel, side panels extending from opposite 55 side edges of and foldable upon the body panel, means to secure the side panels in folded position, a bottom panel and a top 60 panel and means to secure the top panel in folded position with the bottom panel ex- tended to provide a backing for the lower portion of a garment within the protector.

In testimony whereof I affix my signature.
RICHARD WALTER DAWN.
